UNITED STATES PATENT OFFICE.

CHARLES F. SLIFER, OF PHILADELPHIA, PENNSYLVANIA.

COMBINED REFRIGERATOR AND WATER-COOLER.

SPECIFICATION forming part of Letters Patent No. 366,694, dated July 19, 1887.

Application filed September 6, 1886. Serial No. 213,831. (No model.)

To all whom it may concern:

Be it known that I, CHARLES F. SLIFER, a citizen of the United States, residing in the city and county of Philadelphia, State of Pennsylvania, have invented a new and useful Improvement in a Combined Refrigerator and Water-Cooler, which improvement is fully set forth in the following specification and accompanying drawings, in which—

10 Figure 1 represents a side elevation of a combined refrigerator and water-cooler embodying my invention. Fig. 2 represents a vertical section thereof. Fig. 3 represents a longitudinal vertical section of the support for 15 the cooler and of the drip-conveyer on an enlarged scale.

Similar letters of reference indicate corresponding parts in the several figures.

My invention consists of a combined refrigerator and water-cooler constructed of a body of the form of a water-cooler having a cold-air space in its bottom and a door in its side, said space being cooled from the water and ice receiver, which is suspended within said body. 25 Provision is made for supporting said receiver and conveying the drip therefrom to the bottom of the body, all as will be hereinafter set forth.

Referring to the drawings, A represents the 30 body of a water-cooler, which is utilized as a refrigerator, and has suspended within it the water and ice receiver B, whose height is considerably less than that of the body A, so as to form in the body of the latter a cold-air space, C, said receiver being of conical shape, the wide end being above, so as to form the side cold-air space, D. The receiver is provided with a faucet for drawing off the water from the outside of the body A. Connected 35 with the interior of the body below the receiver is a cross-bar, E, having an opening through which passes, without contact therewith, a stem, E', and grooved bolt F, the latter depending from said stem and passing through a plate, F', secured against the under face of the cross-bar. The bolt F is provided with a nut, G, on its lower end, by which provision the joint at the top flange of the receiver and upper end of the body is tightly closed, and 45 the receiver is firmly supported and prevented from improper displacement.

In the side of the body A is a door, II, whereby access is had to the space C.

Connected with the cross-bar E is a drip-conveyer, J, of the form of a trough, which 55 extends in an inclined direction, and has its lower end open adjacent to the inner wall of the body, whereby as the drip from the receiver B trickles down the sides of the same to the center of the rounded or pointed bottom 60 thereof it reaches the stem or bolt F, and, as the sides of the latter are grooved to form ducts, the drip passes through the cross-bar and drops on the conveyer J, and runs down the same to the wall of the body, by which it 65 is directed to the bottom of the body, from which it can be removed by means of a sponge, rag, or other means, it being seen that the drip is prevented from dropping on the food, &c., contained in the space C.

70 In lieu of the ducts in the bolt F, they may be formed in the cross-bar around said bolt and accomplish the same purpose.

By securing the receiver B to the plate and having a space between the stem and the bar, 75 as shown in Figs. 2 and 3, the drip on the outer surface of the receiver is readily conveyed to the stem and bolt, not coming in contact with the bar.

It will be seen that the space C provides 80 means for holding articles of food, &c., to be cooled, the air being cooled from the receiver B, which contains water and ice, the air in the spaces C D being in contact with the receiver, so that there is an effective cooling action.

85 The receiver may be removed by unscrewing the nut G and then lifting it from the body, and it may be restored to position and again secured to the cross-bar, the removability of the receiver permitting the cleansing 90 of the interior of the body and exterior of the receiver, or for other purposes.

The body A is formed of segments or sections A', of wood, firmly secured together, and a lining, A'', of zinc or other suitable non-corrod़ing metal.

The receiver B is formed of cast metal with an enameled lining.

I am aware that it is not new to construct a combined refrigerator and water-cooler having a chamber below the cooler, and to provide the same with means to convey the water

of condensation formed on the outer surface of the water-cooler, so as to fall near the inner wall of the casing, and such I do not claim; but I am not aware that the particular device 5 described herein for sustaining the cooler, and at the same time aid in carrying away the drip, so as to prevent it injuring the contents of the chamber, has ever been employed until by me in this application.

10 Having thus described my invention, what I claim as new, and desire to secure by Letters Patent, is—

15 1. A combined refrigerator and water-cooler consisting of the body A and ice-receiver B, the latter having stem E' and grooved bolt F, with nut G, the cross-bar E, with an opening therein, the plate F', and the conveyer J, the

said stem E' and bolt F passing through the opening in the cross-bar E, substantially as described.

2. A combined refrigerator and water-cooler having a receiver with a stem on its under surface, and a grooved bolt secured to said stem, a cross-bar secured at its ends to the casing and having an opening, a plate through 25 which passes the bolt, and a nut on said bolt, whereby the plate is pressed to the under side of the cross-bar and the receiver is firmly held in position, all of said parts being combined substantially as and for the purpose set forth. 30

CHAS. F. SLIFER.
